UNITED STATES PATENT OFFICE.

ROBERT L. WOODRUFF, OF WINDER, GEORGIA, ASSIGNOR TO WOODRUFF HARDWARE CO., OF WINDER, GEORGIA.

HAY-PRESS.

SPECIFICATION forming part of Letters Patent No. 711,270, dated October 14, 1902.

Application filed March 21, 1902. Serial No. 99,261. (No model.)

To all whom it may concern:

Be it known that I, ROBERT L. WOODRUFF, a citizen of the United States, residing at Winder, in the county of Jackson and State 5 of Georgia, have invented certain new and useful Improvements in Hay-Presses, of which the following is a specification.

My invention relates to improvements in hay-presses; and the object of my invention 10 is the provision of a hay or baling press which will be thoroughly efficient and practical and which can be produced at a very low price to enable the press to be readily available to all persons desiring a useful, durable, practical, 15 and efficient press for baling hay or other material.

With this object in view my invention consists of a hay or baling press embodying novel 20 features of construction and combination of parts, substantially as disclosed herein.

Figure 1 represents a perspective view of my improved hay-press. Fig. 2 represents a side elevation thereof. Fig. 3 represents a vertical central sectional view of the press 25 with the plunger in the pressing-box to its farthest extent. Fig. 4 represents a detail view to show the construction of the plunger and guides in the box.

Referring by numerals to the drawings, in 30 which similar numerals of reference denote corresponding parts in the several views, the numeral 1 designates the casing or press-box, in which the hay or other material is placed to be baled, which box is composed of mate- 35 rial built to form a strong box or casing, and the box near its mouth is provided with the guide strips or cleats 2, which enter kerfs or recesses 3 in the plunger or follower 4 and serve to guide said plunger, and connected 40 to said plunger is the rod or arm 5, which has on its under side a lug 6, which forms an abutment to limit the movement of said plunger-rod, as will presently appear, and to its outer end is secured the metal bracket 7, in 45 which is mounted the stud 8, having journaled thereon the friction or guide roller 9, said roller traveling in the groove or channel 10 of the wheel 11, which wheel is mounted on a vertical post 12, secured to the frame or bed 50 13, which is connected to the box or casing.

The frame 13 is composed of a single flat

board adapted to rest flat upon the ground and is provided with a cross-piece 14 intermediate of its length, against which is adapted to strike the lug or abutment 6 on the 55 plunger-rod when said rod is forced back under the action of the spring 18, connected to the plunger-rod 5 and to the cross-piece 14, and this limits the backward movement of the plunger-rod after the plunger has forced 60 the material into the box, and to the other end of said cross-piece is secured a buffer-spring 15, which receives the impact of the plunger-rod when forced against it by the grooved wheel. 65

The under side of the grooved wheel is formed with teeth 19, with which engages the detent 20, which holds the wheel from rotation in the wrong direction, and to the wheel is connected the tongue or sweep 21, to which 70 the draft attachment is secured to enable the animal to rotate the wheel, and I also mount upon the upper side of the wheel the two antifriction-rollers 22, which when the wheel is rotated by the animal contact with 75 the bracket on the end of the plunger-rod and force the plunger into the press-box. To the upper side of the press-box, near its mouth, is arranged the cross-piece 23, to which are connected the spring-arms 24. 80

The operation of my press will be readily understood from the accompanying drawings, taken in connection with the description, and briefly stated is as follows: The charge of hay is placed in the press-box, and the horse is 85 started, which revolves the power-wheel, which carries the plunger-rod inward and forces the plunger into the box and presses the hay, and the plunger then rebounds under the action of the returning-spring and is 90 limited by the abutment contacting with the cross-piece on the frame or power-bed, when the roller on the power-wheel again contacts with the plunger-rod and forces the plunger into the press-box again and further com- 95 presses the hay, and it will be seen that the single horse revolves the power-wheel and that the rollers on the wheel force the plunger-rod inward, and when released the spring returns the rod ready for the next operation. 100 The end of the plunger-rod 5 carries an antifriction-wheel 9, which revolves in a groove of

the power-wheel, and the antifriction-wheels 22 are arranged slightly over the groove of the power-wheel, so that at the proper time they will engage the bracket on the plunger-rod and force the rod inward with the plunger, and when the friction-wheel 22 passes beyond the bracket the spring 18 returns the plunger-rod for the next compression.

It will be seen that my press can be operated by only two men, and a single horse will furnish ample power, as one man places the charge of hay into the press-box at the mouth and the other man attends to the putting on wires or ties on bales, and in a very short space of time the baling of hay or other material can be effected in a perfect manner. It will also be observed that my press can be easily moved from place to place and stored in a small space and can be quickly set up, as it is only necessary to attach the frame or power-bed to press-box and place the power-wheel in position with plunger-rod connected and in press-box and attach horse to lead-pole and the machine is ready for operation. It will also be noted that my press is of simple, durable, and inexpensive construction and places a practical and efficient press within the reach of all desiring such.

I claim—

1. In a baling-press, the combination of a 30 press-box, a plunger or follower therein, a rod connected to the plunger, a roller on the outer end of the rod, a power-wheel having a groove in which said roller travels and having antifriction devices to engage the end of 35 the plunger-rod to drive the plunger into the press-box, a spring for returning the plunger, and a stop to limit the return movement of the plunger.

2. In a baling-press, the combination of the 40 press-box having retainers on the inner side, the plunger having recesses to receive said retainers, the rod connected to the plunger and having the roller at its outer end, the returning-spring, the stop and buffer, the power-wheel having a groove to receive the roller on the rod, the rollers on the wheel to engage the end of said rod, the sweep connected to the power-wheel, and the teeth on the power-wheel and the detent to engage said teeth to 45 prevent back movement of the power-wheel.

In testimony whereof I affix my signature in presence of two witnesses.

ROBERT L. WOODRUFF.
